UNITED STATES PATENT OFFICE.

GEORGE F. GIRVAN, OF LITTLE FALLS, NEW YORK.

ALARM LETTER-BOX.

SPECIFICATION forming part of Letters Patent No. 378,166, dated February 21, 1888.

Application filed October 17, 1887. Serial No. 252,602. (No model.)

To all whom it may concern:

Be it known that I, GEORGE F. GIRVAN, a citizen of the United States, residing at Little Falls, in the county of Herkimer and State of New York, have invented a new and useful Improvement in Alarm Letter-Boxes, of which the following is a specification.

My invention relates to improvements in alarm letter-boxes; and it consists in the peculiar construction and combination of devices, that will be more fully set forth hereinafter, and particularly pointed out in the claims.

In the accompanying drawings, Figure 1 is a vertical sectional view of a letter-box alarm embodying my improvements, showing the same attached to the panel of a door. Fig. 2 is a front elevation of my improved letter-box alarm, a portion of the lid or cover being broken away. Fig. 3 is partly a top plan view and partly a longitudinal section of my improved letter-box alarm. Fig. 4 is a detached perspective view of portions of the same.

A represents a rectangular neck or collar, which is made of cast metal, and is adapted to be inserted in an opening, B, in a door or window, C, in the usual manner, so as to form an opening in the said door or window, through which mail-matter may be passed to the interior of the compartment or into a letter box or receptacle (not shown) attached to the inner side of the door or window. The said neck or collar A is provided on its outer side with a vertical surrounding flange-plate, D, which bears against the front side of the door or window, and is secured thereto by means of screws E. The front side of the neck or collar is inclined downward and outward, as shown, and the upper flange, D, is provided near its ends with outwardly-projecting lugs or ears F.

G represents a door or lid which covers the inclined outer side of the neck or collar, is provided at its upper edge with lugs or ears H, which are pivotally connected to the ears F by means of bolts or rivets I, and is further provided on its inner side, near its edges, with a groove, in which is placed a rubber or other suitable packing, K, that is adapted to bear against the outer edges of the neck or collar, and thereby effect a tight joint therewith, when the lid or cover is closed, to prevent rain or snow from entering. To the inner side of the lid or cover G, near one end thereof, is se-

cured a segment-arm, L, which is provided on its inner side with a series of teeth or corrugations, M.

N represents an arm which has its upper end pivoted to a lug, O, that depends from the upper side of the neck or collar. The lower end of this arm N bears against a stop or stud, P, on the lower side of the neck or collar when the said arm is in a vertical position.

R represents a concavo-convex gong or bell of suitable size, which is secured to the outer side of the arm N by means of a screw, S, that passes through a central opening in the gong or bell and engages an opening in the arm N. On one side of the gong or bell, which is opposed to the segment-arm L, is formed a lug or offset, T, that is arranged in the path of the teeth or corrugations of the segment-arm.

U represents a coiled retractile spring that has one end connected to the lower end of the arm N by means of a screw, Y, and has the other end attached to a stud, W, near one end of the neck or collar, by means of a screw, X. The function of this spring is to normally keep the arm N in a vertical position, with its lower end bearing against the stop P and the lug or offset T of the gong, arranged within the path of the teeth or corrugations of the segment-arm L.

The operation of my invention is as follows: When the postman raises the lid or door G, in order to introduce mail-matter through the neck or collar, the segment-arm L is swung through a portion of a circle and the toothed or corrugated edge of the same engages the lug or offset T on the gong or bell R, and, as the latter is rigidly connected to the pivoted arm N, causes the said arm to vibrate to and from the stop P, and thereby cause the gong to sound an alarm, as will be very readily understood. When the door or cover G is closed, the same operation is repeated and the alarm is again sounded.

Having thus described my invention, I claim—

1. The combination, in an alarm for letter-boxes, of the lid or door G, having the toothed or corrugated arm L, and the bell or gong attached to a support capable of vibratory motion and engaged by the toothed or corrugated arm, substantially as described.

2. The combination, in a letter-box alarm,

of the hinged door or lid G, having the toothed or corrugated arm L, the pivoted arm N, adapted to vibrate, and the bell or gong R, secured to the said arm N and arranged in the path of the teeth on the arm L, whereby the arm N will be vibrated and the gong or bell sounded when the lid or door is opened or closed, substantially as described.

3. The combination, in a letter-box alarm, 10 of the door or lid G, having the toothed or corrugated arm L, the pivoted arm N, the stop P, the spring pressing the free end of the said arm normally against the said stop, and the gong or bell secured to the said arm and having one edge arranged in the path of the teeth 15 or corrugations of the arm L, whereby the arm N will be vibrated and the bell or gong sounded

when the door G is opened or closed, substantially as described.

4. The combination, in an alarm for letter-boxes, of the lid or door G, having the toothed or corrugated arm L, the vibratory arm N, and the bell or gong attached to said vibratory arm and having one edge arranged in the path of the toothed or corrugated arm L, substantially as described.

In testimony that I claim the foregoing as my own I have hereto affixed my signature in presence of two witnesses.

GEORGE F. GIRVAN.
